HORIZONTAL BURNER

Joseph E. Farrell, Toms River, N. J., assignor to
National Engineering Foundation, Inc., Washington, D. C., a corporation of Delaware

Application June 10, 1942, Serial No. 446,507

2 Claims. (Cl. 158—53)

This invention relates to gaseous fuel burners of the type which convert raw fuel into gas before it is mixed with air to support combustion.

The primary object of the invention is to provide a burner of the horizontal or gun type utilizing dry gas. To that end the invention contemplates novel features of construction for supporting the gas generating means efficiently and effectively in the burner barrel.

A further object of the invention is to provide a construction which is simple to manufacture and easy to install and maintain.

With the above and other objects in view, which will more readily appear as the nature of the invention is better understood, the same consists in the novel construction, combination, and arrangement of parts hereinafter more fully illustrated and described.

A preferred and practical embodiment of the invention is shown in the accompanying drawings, in which

Fig. 1 is a side elevation of a burner embodying the present improvements.

Fig. 2 is a vertical longitudinal sectional view illustrating the improvements on an enlarged scale.

Fig. 3 is a vertical cross sectional view taken on the line 3—3 of Fig. 2.

Fig. 4 is a detail cross sectional view taken on the line 4—4 of Fig. 2.

Similar reference characters designate corresponding parts throughout the several figures of the drawings.

Referring to Fig. 1, it will be observed that the invention includes in its organization, a barrel designated generally as A, which is open at its front end, while its rear end is connected by suitable fastenings to a blower and its casing designated generally as B. The barrel A is surrounded by a hood C which may conveniently be hinged as indicated at D to the upper portion of the blower casing. The general assembly thus described may be mounted on a suitable standard or support E, the same being preferably adjustable through the medium of a threaded base socket and a mating screw stem in order to adjust the barrel A at the desired height from the floor relative to the fire box of the furnace with which it is used.

Within the barrel A there is provided a suitable gas producing means which is supplied with raw fuel through fittings positioned externally of the barrel and covered or housed by the hood C, previously referred to. The gas producing means includes a gasifying retort R and a

flame initiator construction designated generally as F. The retort R and flame initiator F are mounted within a tubular sleeve or carrier G, of less internal diameter than the barrel A, and provided with a plurality of side or radial openings G'. This carrier is concentrically supported within the barrel by means of the spacing washers H which in one instance cooperate with the threaded shank H' of the spark plug S, and in another instance with the screw fastening or its equivalent H². In other words, the threaded shank H' of the spark plug has its lower end threaded into a threaded opening of the carrier G and likewise the shank of the screw H² is threaded into an opening also formed in the forward end of the carrier so that when these elements are in place, the carrier is properly supported and spaced in the barrel.

The flame initiator F preferably includes a cup-like housing I having a side wall provided with ribs 2 offset at desired angular intervals which engage the interior of the tubular carrier G to support the cup-like member in position to provide the air passage 3 around the outside of the same. The bottom of the cup-like member I is provided with a central opening 4 for receiving air from the blower B, and inwardly of said opening the cup-like member is provided with an annular flange 5 which holds an air diffuser 6. The latter preferably consists of a body portion provided with a plurality of openings or channels 7 which direct air coming in through the opening 4 against the pilot 8 supported on a short pipe section 9 connected with the elbow fitting 10 of the initial fuel supply pipe 11. The pilot 8 preferably consists of a pair of discs having flanges which are telescoped to provide a fuel receiving chamber 8a, the discs being held together by the hollow rivets 8b or their equivalent. One side of the pilot 8 is provided with a cup-like windshield 8c for the purpose of deflecting air passage through openings 7 around and about the sides of the pilot. The side walls of the fuel chamber 8a are provided with lateral openings 8d on the upper portion thereof so as to be adjacent to the inner terminal of the spark plug S.

The tubular carrier G is provided medially of its interior with an air deflecting and diffusing member having the skirt 12 which is of less diameter than the cup-like member I and is connected by the curved wall 13 with the annulus 14 which engages the inner face of the carrier G. The skirt 12 and wall 13 cooperate with the inner wall of the carrier G to pick up

air from the blower and return it to the air diffuser 7 so as to increase the volume of air directed against the windshield 8c of the pilot device 8. The annulus 14 is provided with inwardly directed arms 15 which support an aspirating ring 16 which shields the open ends of the gas outlet tubes 17 of the retort, and, at the same time, produces a vacuum as air proceeds from the blower toward the nozzle end of the barrel A, for the purpose of aspirating dry gaseous fuel from the retort R. As will be seen from Fig. 3, the retort R is provided with four aspirating tubes 17.

Referring now more particularly to the retort, it will be observed that the same includes a casing designated generally as 18 which may be formed by a pair of cup-like members whose side walls are telescopically interfitting and whose end walls 19 and 19a are held together by hollow sleeve 20. The interior of the retort is provided with a plurality of annular baffles 21 and 22 which are placed on the sleeve 20 in spaced relation before side walls of the casing 18 are telescoped. The baffle 21 is provided with openings 21a at opposite sides of its axis, that is, above and below the sleeve 20 whereas the baffle 22 is provided with an opening 22a at one point only, above the sleeve 20. Since the baffle 22 is solid except for the opening 22a, it will be apparent that liquid fuel may be trapped in the chamber R' formed by the said baffle 22 and the outer end wall 19 of the casing. The fuel is supplied by the pipe 23 whose discharge end terminates within the chamber just referred to, above the opening 22a. The baffle 21 forms the chambers R² and R³. The retort R consisting of the parts described is centered in the tubular carrier G by the spider 24.

The raw fuel supply pipe 23, above referred to, extends rearwardly from the retort and has a portion thereof bent at an oblique angle so as to bring the intake portion thereof concentric with the pipe 9 previously referred to in connection with the flame initiator unit F. As will be seen from Figs. 2 and 4, the pipe 23 is of smaller diameter than the pipe 9 and extends beyond the fitting 10 to connect with a fitting 25 which is in piped communication with a main supply valve 26. The said valve 26 may also be connected with an auxiliary valve 27 which controls the supply of fuel to the flame initiator through the pipe 11. Both valves 26 and 27 communicate with a tank or other reservoir through the medium of a supply line (not shown) connected with the threaded nipple 28.

In the example illustrated, the main liquid fuel supply valve 26 and the flame initiator valve 27 are connected by a common passage 29. It will, of course, be understood that the valves 26 and 27 may be of any conventional automatic type which respond alternately to thermostat demand. In the present instance, however, these valves are shown as being manually operated which requires manipulation of the stem of each individual valve for starting and sustained operation. For example, if the burner is to be started, the stem of the main supply valve 26 may be manipulated to open position for a brief interval, while the stem of the valve 27 remains closed to permit raw fuel to pass through the pipe 23 to the retort chamber R'. The stem of the valve 26 is then manipulated to close the main supply and the stem of the valve 27 is then open to let a quantity of raw fuel into the pipes 11-9 so as to fill the pilot 8. The sparking device S is 75

activated simultaneously with the supplying of fuel to the pilot and likewise the blower B is started. As a result, the pilot device becomes a flame initiator from which flame is propagated by air supplied from the blower and through the rear end of the barrel A. The auxiliary initial supply valve 27 is closed and the sparking device S is cut off when the flame initiator is activated and then the main supply valve 26 is opened to insure continued supply of fuel to the retort R. Heat from the flame initiator F heats the retort R and gasifies fuel trapped in the chamber R'. The gas passes through the opening or port 22a into the chamber R² where it is further heated and thence into the chamber R³ where it receives its final heating prior to being aspirated through the tubes or pipes 17 by the vacuum producing aspirating ring 16.

It will be apparent that flame from the flame initiator or pilot device will envelope the retort R both directly through the interior of the carrier G and also because the flame can escape through the openings G' in the carrier. After gas generation has been started in the retort and gas is aspirated through the tubes 17, it will ignite in the zone of the openings G' and thus thereafter maintain the retort R in a continuous bath or swirl of flame so that continued gasification of the incoming supply of raw fuel is maintained by the heating flame issuing from the nozzle end of the barrel of the burner.

I claim:

1. A gaseous fuel burner, comprising, in combination, a blower including a housing, a barrel communicating with the blower housing to conduct an air stream therefrom; a gasifying unit disposed in the said air stream of the barrel and including, a tubular carrier of less diameter than the barrel, means for suspending the carrier in the barrel in spaced relation thereto to provide an air space between the carrier and the inner surface of the barrel, a gasifying retort supported at the outlet end of said carrier, said retort having rearwardly extending gas discharge tubes, means for shielding the outlet ends of said gas tubes from the direct blast of the air stream and tending to produce a vacuum in said gas tubes when the air stream passes said means, a flame initiator unit supported in the intake end of the carrier and exposed to the air blast issuing from said blower, said carrier having medial openings for admitting air from the space between the same and the barrel into the carrier in the zone of the gas tubes, valve controlled pipe means leading into the barrel for supplying liquid fuel respectively to the retort and flame initiator, and an igniter device carried by the barrel and having its sparking end disposed in flame propagating proximity to the flame initiator.

2. A gaseous fuel burner of the gun type, including, in combination, a blower and a horizontal barrel for conducting the air stream from the blower, means within the barrel for generating gas from liquid fuel, said means comprising a tubular carrier of less diameter than the barrel and having side openings, means for supporting the carrier in the barrel to provide an air space between the inner face of the barrel and the outer face of the carrier, said space also communicating with said openings in the carrier, a gas generating retort supported in the outlet end of the barrel and having rearwardly extending gas discharge tubes, means shielding the outlet ends of the gas tubes from direct impingement by the air stream and cooperating therewith to induce a

vacuum in the tubes and retort, a flame initiator unit supported at the inlet end of said carrier, means for supplying liquid fuel respectively to the said retort and to the flame initiator unit, and ignition means for starting the flame initiator unit, whereby when liquid fuel is supplied to the retort and the flame initiator unit, and the fuel supplied the latter has been ignited by said igni-

tion means, air from the blower will force the flame from the flame initiator unit through the carrier to engulf the retort in flame to gasify liquid fuel therein whereby gas thus generated and said air will produce a gaseous mixture to sustain flame propagation at the outlet end of the barrel.

JOSEPH E. FARRELL.
